UNITED STATES PATENT OFFICE.

PETER W. SPRECHER, OF MILWAUKEE, WISCONSIN.

ELECTRIC-FIXTURE ATTACHMENT.

Application filed May 16, 1927. Serial No. 191,812.

This invention relates to electric fixture attachments.

Objects of this invention are to provide a novel form of ferrule which is so constructed that it will cooperate directly either with a ceiling canopy or with a pendant bell in a novel manner, and which is so constructed that it may be very readily locked to either the bell or the canopy and may thus be sold as a separate entity to the manufacturer of fixtures, so that he may selectively apply it as desired.

Further objects are to provide a ferrule which definitely positions itself and which may be locked rigidly to the canopy or bell, and which is provided with apertures to selectively receive the supply wires and the attaching screw or screws with either of the two devices with which it may be used.

An embodiment of the invention is shown in the accompanying drawings in which:

Figure 1 is a view partly in section showing the ferrule attached to a ceiling canopy;

Figure 2 is a transverse sectional view on the line 2—2 of Figure 1;

Figure 3 is a view partly in section showing the ferrule attached to a pendant bell;

Figure 4 is a perspective view of the ferrule free from attachment.

Referring to the drawings, particularly Figures 1 and 2, it will be seen that the ferrule has a cylindrical side wall 1 and a transverse wall 2 closing its end. This transverse wall is provided with a central aperture 3 for the reception of the attaching screw 4 when used with a ceiling canopy 5, as shown in Figure 1. The end wall is also provided with a pair of spaced apertures 6 for the reception of the supply wires 7 when used with the ceiling canopy. The cylindrical wall 1 is provided with a pair of diametrically spaced apertures 8 for the reception of the inturned ends 9 of the suspension ring 10.

It may be found preferable to slightly bow the material of the end wall 2 outwardly adjacent the central aperture 3, as shown most clearly in Figure 1.

It is to be noted particularly that the cylindrical wall 1 of the ferrule is provided with an intermediate outwardly folded bead 11 for definitely positioning the ferrule with reference to either the canopy or the suspension bell which latter will be described hereinafter. This outwardly turned bead 11, as may be seen from Figure 1, contacts with the lower end of the ceiling canopy and thus

definitely positions the ferrule. The ferrule is provided with an annular marginal flange 12 which initially forms a continuation of the cylindrical side wall of the ferrule. This flange 12 is adapted to be folded downwardly to thus lock the inturned flange of the canopy or bell in place.

The device may be used with a pendant bell 13 provided with a socket 14, as shown in Figure 3. When it is used in this manner, the bead 11 and the flange 12 are utilized in the same manner to position the ferrule and lock it to the bell. However, the apertures 6 receive the attaching screws 15 which pass through the ferrule and into the socket 14. The central aperture 3 receives the supply wires 16, as shown in Figure 3, and it will be seen therefore that the device is readily adapted to different interchangeable uses with either the bell or with the canopy.

It is apparent therefore that the manufacturer of fixtures does not have to carry in stock two distinct closure members respectively adapted for use with a ceiling canopy or with a pendant bell, but may carry a single type of member, as illustrated and described herewith, which is adapted for attachment to either the canopy or the bell without any alteration whatsoever in its construction.

It is thus apparent that the manufacturer may be supplied with this ferrule and that he may use it in either of two capacities with the utmost freedom and without change.

It will be seen further that the device forms a finish which is attractive and pleasing, and which harmonizes fully with either the bell or the canopy.

It will be seen further that there are no open or unused holes in the device, but that all of the holes are used whether the device is attached to a canopy or a bell.

It is to be noted further that the device may be readily stamped or otherwise formed from sheet metal in a very cheap and economical manner, and may be very readily applied to the bell or the canopy.

Although the invention has been described in considerable detail, such description is intended as illustrative rather than limiting as the invention may be variously embodied and as the scope of such invention is to be determined as claimed.

I claim:

An end ferrule for attachment to either

a ceiling canopy or a pendant bell provided with an interior socket, said ferrule having a cylindrical wall and having a transverse end wall, said transverse end wall having a central aperture and a pair of apertures spaced from said central apertures for the reception of a screw and supply wires respectively when used with the ceiling canopy and for the reception of supply wires and attaching screws for the socket respectively when used with the pendant bell, said cylindrical wall having a pair of apertures,

a suspension ring having its ends seated in the apertures in the cylindrical wall, said cylindrical wall having a bead intermediate its ends and an annular marginal flange, whereby said bead may contact with the end of the canopy or bell and the flange may project into the canopy or bell. 15

In testimony that I claim the foregoing 20 I have hereunto set my hand at Milwaukee, in the county of Milwaukee and State of Wisconsin.

PETER W. SPRECHER.
